UNITED STATES PATENT OFFICE.

AARON BERMAN, OF NEW YORK, N. Y., ASSIGNOR TO SAMUEL ELGART AND
DINA BERMAN, OF NEW YORK, N. Y.

GARMENT.

No. 851,488.

Specification of Letters Patent.

Patented April 23, 1907.

Application filed November 30, 1906. Serial No. 345,668.

To all whom it may concern:

Be it known that I, AARON BERMAN, a citizen of the United States, and a resident of the city of New York, borough of Brooklyn, in 5 the county of Kings and State of New York, have invented a new and Improved Garment, of which the following is a full, clear, and exact description.

This invention is an improved garment, 10 having a special reference to dresses and shirt-waists for children, or other like garments.

The object of the invention is to so construct the dress or shirt-waist that it may be 15 readily and conveniently slipped on and off, especially avoiding the use of buttons or other like attaching devices for holding the garment on the body.

Reference is to be had to the accompanying 20 drawings forming a part of this specification, in which similar characters of reference indicate corresponding parts in all the figures.

Figure 1 is a front elevation of a child's dress embodying my improvement, showing 25 the same as it would appear when in use; Fig. 2 is a front elevation of the upper portion of the dress disclosing the manner in which the tie and dress are connected; Fig. 3 is a view similar to Fig. 2 with the neck of the 30 dress expanded as when removing or placing it on the body, and Fig. 4 is a cross section of the dress.

1 indicates a child's dress of any desired 35 shape or pattern, but with the front thereof formed with an excess of material in order to provide a box-pleat 2 at its center, preferably running the entire length of the dress and adapting the neck-band of the dress to be expanded or contracted by folding or opening 40 said pleat.

The upper corners of the pleat are elongated and reinforced as shown in Figs. 2 and 3, and have attached thereto tie-ends 3, which are passed through loops 4 sewed to 45 the neck over the shoulders of the garment and normally covered by a collar 5.

In applying the garment, it is only necessary to withdraw the tie-ends 3 from the loops 4 a short distance, as illustrated in Fig. 50 3. The plate 2 can then be opened, expanding the neck of the garment sufficiently to admit of the head being passed through it. The tie-ends are then pulled through the loops to close the pleat and contract the neck, 55 as illustrated in Fig. 2, after which said ends

are tied together to form a neck-tie if desired, and the collar turned down as illustrated in Fig. 1.

By elongating the corners of the box-pleat and reinforcing them as stated, the wear on 60 the loops 4 is removed from the tie-ends and brought to bear on said corners, as shown in Fig. 2, thereby strengthening and prolonging the wearing qualities of the garment at these points. 65

Having thus described my invention I claim as new and desire to secure by Letters Patent:

1. A garment having a pleat formed in the neck thereof, loops attached to the garment 70 at opposite sides of the neck, and tie-ends attached to the pleat adapted to pass through said loops, for closing said pleat.

2. A garment having a box-pleat formed in the neck thereof, loops attached to the neck 75 of the garment at opposite sides, and tie-ends attached to the corners of said pleat adapted to pass through said loops acting when drawn together to close said pleat.

3. A garment having a box-pleat formed in 80 the center of the front thereof, loops attached at opposite sides of the neck of said garment, and tie-ends attached to the upper corners of said pleat adapted to be passed through said loops for closing the pleat, for the purpose de- 85 scribed.

4. A garment having a box-pleat in the front thereof, said pleat having its corners adjacent to the neck of the garment elongated, loops attached at opposite sides of the 90 neck of the garment, and tie-ends attached to said elongated corners adapted to be passed through said loops for holding the pleat closed to contract the neck of the garment, as described. 95

5. A garment having a box-pleat formed at the outside and in the neck thereof, tie-ends secured to the pleat for holding it closed whereby the neck opening of the garment is contracted, said pleat being adapted to be 100 opened out when released by said tie-ends, whereby the neck opening is expanded, for the purpose described.

In testimony whereof I have signed my name to this specification in the presence of 105 two subscribing witnesses.

AARON BERMAN.
